UNITED STATES PATENT OFFICE

110,230

DESIGN FOR A CORNER ORNAMENT FOR A CASKET OR THE LIKE

Edwin H. Thoresen, Chicago, Ill., assignor to William Thoresen Company, Chicago, Ill., a corporation of Illinois

Application April 9, 1938, Serial No. 76,409

Term of patent 3½ years

To all whom it may concern:

Be it known that I, Edwin H. Thoresen, a citizen of the United States, and residing at Chicago, county of Cook, and State of Illinois, have invented a new, original, and ornamental Design for a Corner Ornament for a Casket or the like, of which the following is a specification, reference being made to the accompanying drawing, forming a part thereof.

Figs. 1 and 2 are side elevational views at right angles to each other of a corner ornament for a casket or the like, showing my new design; and Fig. 3 is a top plan view of the same.

I claim:

The ornamental design for a corner ornament for a casket or the like, substantially as shown.

EDWIN H. THORESEN.
